UNITED STATES PATENT OFFICE

ALFRED GEORG HANSEN, OF CATHLAMET, WASHINGTON.

SHOESTRING-FASTENER

1,101,277.

Specification of Letters Patent. Patented June 23, 1914.

Application filed March 11, 1913. Serial No. 753,556.

To all whom it may concern:

Be it known that I, ALFRED GEORG HANSEN, a citizen of the United States, residing at Cathlamet, in the county of Wahkiakum 5 and State of Washington, have invented certain new and useful Improvements in a Shoestring-Fastener, of which the following is a specification, reference being had therein to the accompanying drawing.

10 This invention relates to shoes and has for its object the production of an efficient binding means to which the laces may be bound after the shoe has been laced, and means for engaging the free ends of said laces.

15 Another object of this invention is the production of an efficient clamping member which is adapted to engage the laces of a shoe, and which is provided with means for preventing the same from becoming loose.

20 25 30 35 40 45 50 55 60 65 70 75 80 85 90 95 100 105 110

With these and other objects in view this invention consists in general of certain novel combinations, constructions, and arrangement of parts, as will be hereinafter fully described, illustrated in the accompanying drawings, and specifically claimed.

In the accompanying drawing: Figure 1 is a front elevation of the portion of a shoe showing the device as constructed in accordance with the invention. Fig. 2 is a transverse section through a portion of the shoe and through the binding member and clamping member. Fig. 3 is a top plan view of the clamping member. Fig. 4 is a top plan view of the binding member. Fig. 5 is a top plan of the blank which forms a supporting plate for the binding member. Fig. 6 is a side elevation of the binding arm showing a portion of the same in longitudinal section.

In the accompanying drawing it will be seen that the device is used in combination with the usual shoe 1 and the laces 2. Carried near the upper portion of the shoe there is 45 a binding member which constitutes the supporting plate 3 which carries the anchoring spurs 4. It will be seen that these anchoring spurs 4 are bent at right angles to the supporting plate 3 and are passed through the shoe at which time they are again bent as illustrated in Fig. 2, for holding the supporting plate upon the shoe. This plate carries a plurality of projecting neck portions 5 upon which the heads 6 are positioned. In 55 use after the shoe has been laced the laces

are then wound around the neck 5 as illustrated in Fig. 1, for preventing the same from coming loose after which the free ends are engaged by the clamping member. This clamping member comprises the supporting plate 7 which carries the anchoring spurs 8 which are formed similar to the anchoring spurs 4 and which allow the supporting plate 7 to be attached to the shoe similar to the supporting plate 3. Struck from the body portion of the supporting plate 7 there are a pair of pivot ears 9 which are provided with the apertures 10. The clamping arm 11 is pivotally secured to these ears by means of the pin 12 which fits within the aperture 10. This clamping arm 11 is provided with a pocket portion 13 adjacent which is formed the inwardly bent portion 14. When the device is in use the pocket portion 13 is adapted to receive the laces 2, 75 as illustrated in Fig. 2, and the bent portion 14 forms a means for preventing said laces from slipping out of the pocket 13. At the other end of the clamping arm 11 there is formed a spring containing pocket 15 which is adapted to receive the spring 16 when the device is in its correct position. The plate 7 is also provided with the lug 17 over which the spring is placed. By use of this lug it will be seen that the spring will be prevented 85 from moving laterally or otherwise upon the plate, but that the lug is sufficiently short as to allow the clamping arm to be swung and the spring compressed since this lug 17 will pass up into the pocket 15.

By referring to the foregoing description it will be seen that a device has been produced whereby the laces will be securely held after the shoe has been laced and that the free ends of the lace will be so held as to prevent the laces from becoming loosened.

Having thus described the invention what is claimed as new, is:—

A shoe-string clamp comprising a base plate, a plurality of retaining spurs formed upon the outer periphery of said plate for holding said plate upon a shoe, pivot ears struck from said plate and extending at right angles thereto, an arm pivotally secured to said ears, said arm being bent to form a pocket-portion and terminating in an inwardly-bent portion forming an entrance lip, said inwardly-bent portion of said arm resting firmly upon said plate whereby said pocket-portion will be posi-

tioned at a spaced distance from said plate for the accommodation of a shoe-string, said ears limiting the inward movement of the strings within said pocket, and a spring carried by said plate and bearing upon said arm for holding said inwardly-bent portion in engagement with said plate.

In testimony whereof I hereunto affix my signature in presence of two witnesses.

ALFRED GEORG HANSEN.
